LADY'S HEAD COVERING

Iris G. Sibley, New Hope, Pa.

Application August 10, 1953, Serial No. 26,358

Term of patent 14 years

(Cl. D3—13)

To all whom it may concern:

Be it known that I, Iris G. Sibley, a citizen of the United States, residing in the city of New Hope, county of Bucks, and State of Pennsylvania, have invented a new, original, and ornamental Design for a Lady's Head Covering, of which the following is a specification, reference being had to the accompanying drawing, forming a part hereof, in which:

Fig. 1 is a side elevation of a lady's head covering embodying my new design.

Fig. 2 is a front elevation thereof.

Fig. 3 is a top plan view; and

Fig. 4 is a perspective view thereof as it appears in draped or wearing position.

I claim:

The ornamental design for a lady's head covering, as shown and described.

IRIS G. SIBLEY.
